J. F. FARRINGTON

TRANSMISSION CIRCUITS

Filed July 31, 1923

UNITED STATES PATENT OFFICE.

JOHN F. FARRINGTON, OF FLUSHING, NEW YORK, ASSIGNOR TO WESTERN ELECTRIC COMPANY, INCORPORATED, OF NEW YORK, N. Y., A CORPORATION OF NEW YORK.

TRANSMISSION CIRCUITS.

Application filed July 31, 1923. Serial No. 654,824.

The invention relates to transmitting circuits and particularly to a transmitting system employing a change-over switch which in one position connects the transmitting conductor to the transmitting and receiving circuits for simultaneous transmission and reception, and in its other position connects the transmitting and receiving circuits for use separately in accordance with the operation of a push button which controls a transmit-receive relay to alternately connect the transmitting and receiving circuits to the transmitting conductor.

In operating a circuit of this character, especially where the transmitting conductor is a radio antenna as in the preferred form of the invention, it has been found that when the anode circuits of the vacuum tubes in the transmitting circuit are made or broken to change from receiving to transmitting, or vice versa, or to change from simplex to duplex operation, or vice versa, surges of current are caused in the vacuum tube circuits of sufficient intensity to trip the circuit breaker or blow the fuses in the direct current power supply, or in some cases the tubes themselves are rendered temporarily or permanently inoperative.

An object of the invention is to prevent surges of current in the tube circuits in order that the transmitting circuit may be maintained in an operative condition. This is accomplished by permanently connecting in circuit a sufficient number of the vacuum tube devices, so that the surges due to switching on and off the remaining tubes, are not objectionably large.

With a circuit of the above mentioned type it has been proposed to use, when the circuit is connected for duplex operation, a trap or anti-resonant circuit, tuned to the transmitted frequency, in order to keep currents of this frequency out of the local receiving circuit, which also includes a tuned circuit. It has been found in adjusting the circuit that, if the trap is out of tune, in tuning the receiving circuit a condition may be reached where the reactance of the trap is neutralized by the reactance of the receiving circuit. This results in abnormally large potentials being applied to the receiving circuit.

Another object of the invention is to protect the receiving circuit against such ab-

normal potentials. This is accomplished by preventing the abnormal potentials from reaching the receiving circuit, for instance, by connecting a protective gap across the receiving circuit. Preferably this gap comprises closely adjacent stationary contact points of the change-over switch, in order that this switch when in a position for simplex operation will short circuit the receiving circuit. Circuit connections are also provided whereby the switching operation just mentioned also serves to short circuit the trap.

For further details of the invention, reference may be made to the drawings wherein a radio signaling circuit adapted for simplex and duplex operation is schematically represented.

Referring in detail to the drawings, the voice amplifier V, the modulator tube M, the oscillator tube O, and the high frequency amplifier HA, are electron discharge devices connected substantially as shown in British Patent No. 168,056, to supply modulated high frequency oscillations.

The alternating current power supply for all of the filaments which are connected in parallel is that of U. S. Patent No. 1,432,022, and will not be described in detail here.

The generator 1 which is provided with a suitable low pass filter 2 supplies direct current to the anode circuits of all of the tubes.

It is to be noted that the anode circuit of tube V is permanently connected to the generator 1, at least its anode circuit is independent of the transmit-receive relay 3, whereas, the anode circuits for the other three tubes are completed through contacts 4 and 5 of this relay. The reason for this has been explained above and is to prevent surges from rendering the circuit inoperative when the generator 1 is connected to the plates or anodes of the tubes. Preferably a condenser 30, connected in shunt to contacts 4 and 5, is employed to prevent sparking at these contacts.

The inductances 6, 7 and 8 in the anode circuits of tubes M, O and HA, respectively, prevent parasitic oscillations, as described and claimed in the U. S. patent to Schelleng, No. 1,437,021—November 28, 1922.

In order to prevent high frequency currents in the output circuit of the tube HA from being supplied to the previous tubes

in the series, the high frequency filter comprising the inductance 9 and condenser 10, is employed. As shown, this filter comprises only a single section, the series element being the high frequency choke coil 9, and the shunt element being the condenser 10 which passes the high frequency currents readily. Obviously, a filter comprising a plurality of sections could be used in place of the single section filter shown.

The coil 11 in the output circuit of tube HA serves to transmit to the antenna the modulated high frequency waves, the connection of this coil in the antenna circuit being as follows: ground 12, tuning inductance 13, condenser 14, coil 11, condenser 10, ground 12. The current in section 13 of the tuning inductance induces a potential difference between the ground 12 and the antenna 15 through the transformer action of the tuning inductance 13. The antenna circuit includes, if desired, a variometer 16 and condenser 17.

The receiving apparatus which may be of any desired type is shown as inductively coupled to a circuit 18, grounded at 19 and tuned to the desired frequency.

For simplex or push-button operation, the double-pole double-throw switch S is thrown to the right. The circuit is then in condition to be changed from transmit to receive in accordance with the operation of the push button 20. When this push button is operated, relay 3 is energized or deenergized over an obvious circuit. With relay 3 in the position shown, the transmitting circuit is connected through contacts 21 and 22 of relay 3 to the antenna 15, and the receiving circuit is short-circuited between ground 12 and ground 19 over an obvious circuit which includes the contacts 23 and 24 of relay 3, the stationary contacts 25 and 26 and blade 27 of switch S. The trap circuit T is tuned to the high frequency to be transmitted, but with switch S to the right as just assumed, this trap circuit is short-circuited through contacts 25 and 26, and blade 27 of switch S. With relay 3 deenergized the receiving circuit R is connected to the antenna over an obvious circuit, the transmitting circuit then being disconnected.

With the switch S thrown to the left, the circuit is adapted for duplex operation, the antenna now being connected both to the transmitting circuit, as previously traced, as well as to the receiving circuit through blade 27, trap T, and contacts 23 and 24 to circuit 18. The blade 28 of switch S now energizes relay 3 through the grounded stationary contact 29 independently of the push button 20.

A protective gap, as above described, is provided for the receiving circuit by the spaced switch contacts 25 and 26, contact 25 being connected to the ungrounded side of

circuit 18 and contact 26 being connected to ground 12. Any excessive potentials produced by the adjustment of circuits T and 18 are prevented from injuring the receiving circuit by being shunted to ground through 70 the gap 25, 26.

What is claimed is:

1. The method wherein a vacuum tube transmitting circuit is operatively related to an outgoing line for transmitting or is inoperatively related thereto, which comprises leaving the anode circuit of one of said tubes energized, and in reducing the energization of the anode circuit of another tube when said transmitting circuit is inoperatively related to the outgoing line. 75

2. A transmitting circuit comprising a plurality of vacuum tube devices, a source of potential for the anodes of said devices, and a change-over switch for disconnecting one of said devices from said source for rendering said transmitting circuit ineffective while leaving another of said devices connected thereto. 85

3. A combined sending and receiving circuit comprising a trap circuit tuned to the sending frequency, a protective gap in shunt to the receiving circuit, and switching means consisting of contacts and a movable arm for bridging said gap and short-circuiting said trap circuit. 90

4. A simplex-duplex sending and receiving circuit comprising a trap circuit tuned to the sending frequency and effective for duplex operation, and switching means for rendering said trap circuit and said receiving circuit ineffective when transmitting simplex. 100

5. In a simplex-duplex transmitting and receiving system, means for preventing abnormal surges in the transmitting circuit when the transmitter is deenergized and means for preventing abnormal surges in the receiving circuit when the transmitter is energized. 105

6. In a transmitting system containing vacuum tubes, means for rendering said system inoperative for transmission, and means for removing the anode potential from certain of said tubes when the transmitter is 115 inoperative while leaving the potential applied to other of said tubes.

7. In a simplex-duplex transmitting and receiving system, means for preventing abnormal surges in the transmitting circuit when the transmitter is rendered inoperative in simplex operation and means for preventing abnormal surges in the receiving circuit in duplex operation. 120

8. In a simplex-duplex transmitting and receiving system, switching means to adapt the circuit to duplex or simplex operation, means for preventing abnormal surges in the transmitting circuit when the transmitter is rendered inoperative in the simplex 125 130

operation, and means for preventing abnormal surges in the receiving circuit in duplex operation.

9. In a simplex-duplex transmitting and receiving circuit containing vacuum tubes, means for removing the anode potential from certain of said tubes while leaving the potential applied to other of said tubes when the transmitter is rendered inoperative in simplex operation and means comprising a trap circuit to prevent abnormal surges in the receiving circuit in duplex operation.

10. In a simplex duplex transmitting and receiving system containing space discharge devices, means for removing the anode potential from certain of said tubes while leaving the potential applied to other of said tubes when the transmitter is rendered inoperative in simplex operation, and means comprising a trap and safety gap to prevent abnormal surges in the receiving circuit in duplex operation.

11. In a simplex-duplex transmitting and receiving system containing space discharge devices, a trap and safety gap to prevent abnormal surges from injuring the receiving apparatus in duplex operation, and a switch to short circuit said gap in simplex operation.

12. In a simplex-duplex transmitting and

receiving system containing space discharge tubes, a switch for changing from simplex to duplex operation, an antenna change-over switch for simplex operation, a trap and safety gap short circuited by said first mentioned switch in simplex operation, and means for breaking the plate circuit of certain of said tubes controlled by said second mentioned switch in receiving position.

13. A method of preventing abnormal surges in a transmitting system when the transmitter is rendered inoperative which comprises removing the potential from the anodes of certain of said tubes while leaving potential applied to the anodes of other of said tubes.

14. A method of preventing abnormal surges in a duplex-simplex transmitting and receiving system including vacuum tubes which consists of removing the potential from the anodes of certain of said tubes while leaving the potential applied to anodes of other of said tubes when the transmitter is rendered inoperative in simplex operation and inserting a protective device to protect the receiver from abnormal surges in duplex operation.

In witness whereof, I hereunto subscribe my name this 24th day of July A. D., 1923.

JOHN F. FARRINGTON.
